REGISTER TRANSFER MECHANISM

Joseph C. Woodford, Haverford, Pa., assignor to
 John Wood Manufacturing Company, Inc.,
 Conshohocken, Pa., a corporation of Delaware

Original application October 31, 1934, Serial No.
 750,805. Divided and this application April 22,
 1935, Serial No. 17,691

1 Claim. (Cl. 235—133)

This is a division of my application Serial No. 750,805 filed October 31, 1934, for Letters Patent of the United States for Improvement in computing and registering mechanism for liquid dispensing apparatus. Said registering mechanism includes pairs of rotary dials respectively indicating units and fractions of units for cooperative display through windows in a stationary panel. For instance, one pair indicates gallons and fractions of a gallon and the other pair indicates dollars and fractions of a dollar. The claims herein relate to the means for turning the unit dial from one unit mark to the next instantaneously upon the completion of each rotation of the fractional dial.

As hereinafter described, such means conveniently includes a spring continually stressing the unit dial to advance it and an escapement controlling said spring and means for releasing said escapement by movement of the fractional dial.

My invention includes the various novel features of construction and arrangement herein-after more definitely specified.

In said drawings, Fig. I is an elevation of said panel and the dial structure provided with indicating means adapted for registration with the windows in said panel.

Fig. II is a vertical sectional view of the computing and registering mechanism including said dials, taken on the line II, II in Fig. I.

Fig. III is a fragmentary plan view showing the connections for operating the dollars dials by the cents dials, which dials are in coaxial relation, as shown in Fig. I.

Fig. IV is a fragmentary vertical sectional view, taken on the line IV, IV in Fig. III, in the direction of the arrows on said line.

Fig. V is a fragmentary vertical sectional view, taken on the line V, V in Fig. III, in the direction of the arrows on said line, showing the escapement for the spring connection between said dollars and cents dials.

Fig. VI is a fragmentary vertical sectional view, taken on the line VI, VI in Fig. III, showing the spring pressed pawl and one toothed ratchet connecting the coaxial shafts of said dollars and cents dials.

Referring to Fig. I, the stationary panel 1 has the window 2 for the display of rotary dials 3 and 4 respectively graduated with circumferential series of marks indicating fractions of a gallon and gallons, which marks are caused to successively register with the stationary index pointers 5 and 6. Said panel has the window 8 for the display of rotary dials 9 and 10 graduated with

circumferential series of marks indicating fractions of a dollar and dollars, which marks are caused to successively register with the stationary index pointers 11 and 12.

Referring to Fig. II; said dial 10 is rigidly connected with the axial shaft 14 which is journaled in the opposite end walls 15 and 16 and the intermediate wall 17, which are rigidly connected by the bottom wall 18 and the top wall 20 to form a casing for the mechanism for turning said dials. Said shaft 14 is encircled by the spring 21 which has its right hand end shown in Fig. III fixed in the hub of the ratchet 22 also shown in Fig. V, on said shaft, and its opposite end fixed in the lever 23 which is fulcrumed on said shaft 14 and has its outer end continually engaged with the stud 24 on said intermediate frame wall 17. Said spring 21 is initially wound on the shaft 14 so that in zero position of said dollars dial 10, said spring is subjected to such torque as to enable it to turn said shaft 14 a complete revolution, clockwise as seen in Fig. V, with such force as to continually hold it and said dial 10 in proper position, determined by the engagement of said ratchet wheel 22 by the escapement shown in Fig. V, as said spring unwinds. Said spring is rewound to its original tension by the operation of setting back the registering mechanism to its zero position, after each dispensing operation, as hereinafter described, by means of the gear pinion 26 which is rigidly connected with said shaft 14 and in mesh with the sectoral gear 27 which is loose on the cents dials connecting shaft 28. Said spring 21 is permitted to advance said dollars dial 10 by means of the escapement illustrated in Figs. III and V, including the ratchet wheel 22. Said ratchet wheel has, in cooperative relation therewith, the two escapement pawls 31 and 32 which are both fulcrumed on the pin 33 in the bracket 34 rigidly connected with said wall plate 16, as indicated in Fig. III. However, as indicated in Fig. V, the sole difference between said pawls 31 and 32 is that the pawl 32 is shorter from its fulcrum to its edge engaging said ratchet 22 than the pawl 31. Both of said pawls are pressed into cooperative relation with said ratchet 22 by the spring 35, the respective bifurcations of which independently press upon said pawls.

Said pawls 31 and 32 are tripped in succession by respective tappets 37 and 38 so as to successively engage each tooth of said ratchet 22 and prevent escapement of more than one tooth thereof at each revolution of said tappets. Said tappets are rigidly connected with each

other and with the circumferential flange 39 by the sleeve 40 which is loose on said shaft 28 but operatively connected to be turned by said shaft counterclockwise in Fig. V by means of 5 the pin pawl 42 carried by the collar 43 which is rigidly connected with said shaft 28 by the set screw 44 shown in Fig. III. Said pin pawl 42 is continually stressed inward by the spring 45 shown in Figs. III and V which is connected 10 at one end to said collar 43; so that said pin pawl (which is like that shown in Fig. VI) engages the single toothed ratchet 46, as shown in Fig. V, to normally turn said tappets 37 and 38 counterclockwise in Fig. V, as if they were 15 rigidly connected with said shaft 28. That ratchet and pawl connection between said shaft 28 and said tappets 37 and 38 is merely to permit said shaft to be turned clockwise independently of said tappets during the resetting operation 20 which winds said spring 21, because said tappets cannot be turned in that direction, being stopped by contact of the tappet 38 with the free end of the pawl 32, as may be observed with reference to Fig. V. Said circumferential 25 flange 39 merely serves to separate the free ends of said pawls 31 and 32, as indicated in Figs. III and V, so as to prevent them from interfering with each other.

Said shaft 28 turns counterclockwise in Fig. 30 V and with the effect that at the completion of each revolution of the cents dial 9, said pawl 31 is first tripped, by the tappet 37, to permit the shaft 14 and its ratchet 22 to turn the slight angular extent from engagement with the pawl 31 to engagement with the pawl 32; so that the pawl 31 is replaced in contact with the ratchet 22 shown in Fig. V, past the crest of the tooth of said ratchet caught by said pawl 32. Thereupon, the pawl 32 is tripped, by the tappet 38, 40 so as to permit said shaft 14 and ratchet 22 to turn the angular extent from one of the ratchet teeth to the next, which is stopped against the end of said pawl 31, in the position shown in Fig. V, thus advancing said dollars dial 10 the extent of one dollar, i. e., one-tenth 45 of a revolution for each revolution of said cents dial 9.

As shown in Fig. II, said cents dial 9 is rigidly connected with the tubular shaft 47 which is conveniently journaled on said shaft 14 and carries the gear 48 by which it is turned, being driven by the pinion shaft 49 of the computing mechanism which is the subject matter of my original application aforesaid. Said gear 48 is only frictionally engaged with said shaft 47 by means of the spring 51 interposed between said gear and the collar 52 pinned on said shaft 47 so as to thrust said gear into frictional contact with the clutch ring 53 between said gear 48 and the collar 54 on said shaft. Such frictional engagement permits said dial 9 to be reset to its initial position without rotation of said gear 48 which is then held stationary by its engagement with the computing mechanism pinion 49.

65 The gear 56 is rigidly connected with said tu-

bular shaft 47, as indicated in Fig. II, and, as indicated in Fig. III, is engaged with the gear 57 on said shaft 28 so that the latter makes one revolution for each revolution of said cents dial 9, to turn the tappets 37 and 38 as above described. Said shaft 28 is turned to reset said dial 9 to zero position by manually operative means including the gear 58 shown in Fig. III, which is frictionally engaged with said shaft 28 by the spring 60 interposed between said gear and the collar 61 which is rigidly connected with said shaft by the set screw 62. Said spring thrusts said gear axially upon said shaft 28 so as to engage the friction disk 64 with the collar 65 which is fixed on said shaft 28. Said dial 9 is stopped in zero position by the pin 66 on the latch 66' which is hung on said stud 24, as shown in Figs. III and IV. The zero position is reached when the inner end of the notch 27' in the sectoral gear 27 encounters said pin 66.

As indicated in Fig. II, I find it convenient to duplicate said stationary panel and rotary dials at opposite ends of said casing so as to simultaneously manifest the similar dial numbers upon said opposite ends. Said panels are 25 respectively supported in rigid relation with said end walls 15 and 16 by brackets 67 and 68.

Although I have found it convenient to form said ratchet 22 with ten teeth for registration of monetary value upon the decimal system, it 30 may be otherwise formed. Therefore, I do not desire to limit myself to the precise details of construction and arrangement herein set forth, as it is obvious that various modifications may be made therein without departing from the essential features of my invention, as defined in the appended claim.

I claim:

In a tens-transfer mechanism; the combination with two rotary members respectively of 40 a higher and lower decimal order, of means for effecting a rotary movement of the member of the higher order by each complete rotation of the member of the lower order, including a spring, continually stressing said member of the 45 higher order to advance it; means for controlling the advancement of said member of the higher order, including an axial shaft in rigid relation therewith, a ratchet wheel in rigid relation with said shaft, two pawls, of respectively 50 different length, for engaging said wheel in circumferentially spaced relation thereto; means for effecting escapement of said wheel from one tooth to the next with respect to said pawls, including two rotary tappet cams in circumferentially spaced relation; means for revolving said tappet cams; and means operatively connecting said cams with said member of the lower order to automatically trip said pawls at each rotation of the latter member; whereby said pawls are 55 successively tripped by said cams, and successively engage each tooth of said wheel, and limit each movement of said rotary member of the higher order to the angle between adjoining teeth of said wheel.

JOSEPH C. WOODFORD. 65
